UNITED STATES PATENT OFFICE.

MARCEL K. SESSLER AND HEYMAN ROSENBERG, OF NEW YORK, N. Y., ASSIGNEES TO
PARKER SUPPLY COMPANY, OF NEW YORK, N. Y., A CORPORATION OF NEW YORK.

RAILWAY-SPIKE.

1,192,125.

Specification of Letters Patent. Patented July 25, 1916.

Application filed August 18, 1915. Serial No. 46,022.

To all whom it may concern:

Be it known that we, MARCEL K. SESSLER and HEYMAN ROSENBERG, citizens of the United States of America, residing at New York city, county of New York, State of New York, have invented certain new and useful Improvements in Railway-Spikes, of which the following is a full, clear, and exact description.

10 This invention relates to an improvement in railway spikes to hold the rails in position on the ties.

Our improvement is directed mainly to a novel form of spike designed to remain firmly embedded in the tie when driven home. In other words our improved spike will not loosen, or cannot be pulled out by the jarring action of the passing trains; hence the spreading and overturning of rails is prevented, as the rails cannot spread or turn over unless the spikes give way. The loosening of a spike permits it to be pulled out or to be shifted sufficiently to cause the rails to spread or turn over.

25 To carry our invention into practice, we take a strip of suitable material, steel for instance, and twist the same to any desired extent by drawing the same through dies or otherwise. While twisting the material, we form a projecting ridge or fin which extends throughout the length of the twist imparted to the strip of material. After having formed the shank of the spike to be, we head the same by suitable dies, a certain portion of the shank adjacent the head being squared and not twisted. The foregoing is an outline of our invention.

We will now proceed to describe our invention, in detail, the essential features of which will be summarized in the appended claims, reference being had to the accompanying drawing, forming part hereof, wherein—

Figure 1 is a sectional view, partly in elevation, illustrating our improved spike as applied to a rail; Fig. 2 is an enlarged side elevation of our improved spike looking toward one of the untwisted sides of the upper part of the shank; Fig. 3 is a sectional view thereof, the section being taken on a line 3—3 in Fig. 2; Fig. 4 is a sectional view, the section being taken on a line 4—4 in Fig. 2; Fig. 5 is a sectional view illustrating a modified form of spike; Fig. 6 is a detail view of the lower end of

the spike illustrating a modified form of piercing point; and Fig. 7 is a detail view of the upper portion of the spike provided with a plain head.

As herein embodied, our invention consists of a spike 1 having a twisted shank at 2 but square and not twisted at 3, the said shank being provided with a head 4 having an annular groove 5 for the insertion of a claw-bar. To fit the tapered flange 6 of a rail 7, we provide the head 4 with an angularly disposed under surface 8, the said surface merging into a fillet 9 at the point where the shank 1 and head 4 join. The shank 1 will be twisted to any desired extent, preferably by drawing the same through dies but we do not limit ourselves to this particular operation. One of the features of our invention is the provision of projecting ridges or fins 10 which extend throughout the twisted portion of the shank 1, the said ridges or fins merging into the corners 11 of the squared portion 3 of the shank. As can be seen in Fig. 4, the twisted portion 2 of the shank 1 consists of a parallelogram having extended corners to form the said projecting ridges or fins. The extended side of the parallelogram joining one side 10^a of the ridge, the other side 10^b of the ridge being angularly disposed, relative to the adjacent side of the parallelogram, to form an obtuse angle. The shank 1 is preferably provided, at its lower end, with a piercing point 12. The head 4 is provided with the annular recess 5 to permit of the insertion of a claw-bar to pull the spike out of the tie 13.

For reasons, which we will explain, the head 4 is preferably made circular although the usual spike head can be used. The circular head is preferable for the reason that it is not necessary to place the spike in any particular position, to bring the head in proper position upon the flange 6, when the spike is driven home. Should the ordinary head be used, it would be necessary to place the spike in a position, before being driven, to cause the head thereof to come to rest upon the flange in the proper position when the spike is driven home, owing to the fact that the said spike will rotate while being driven. In other words, if the spike has a one-quarter twist, the head would have to be positioned parallel with the rail before being driven. In the hands of the ordinary

track workman, this might cause trouble and delay. By employing a round head, the positioning of the spike can be disregarded.

5 Our improved spike will not split the ties or will not back off due to the jarring of the track structure. When the spike is driven in, it will naturally rotate; but should it tend to back off, the ridges 10 will 10 act as an abutment. To remove the spike, a claw-bar would be inserted in the groove 5 of the head 4, but even this operation would require great force.

When our improved spike is used, the tie-15 plates, one being illustrated by 14, will be provided with circular openings 15. The extent of the squared portion 3 of the shank 1 will be slightly greater than the combined thickness of the edge of the flange 6 and 20 tie-plate 14; hence when the spike is driven home, a part of the squared portion 3 will enter the opening made by the spike and fill or plug said opening, whereby water is 25 prevented from soaking into the tie through the opening made by the spike.

Instead of forming the ridges or fins, as shown in Fig. 4, we may form them as shown in Fig. 5, in which the fins are indicated by 16. In this form, the fins have 30 parallel walls 17 and 18. Instead of stopping the fins or ridges at the point where the piercing point 12 commences, as shown in Fig. 2, we may extend the same to the end of the point, as shown at 19, Fig. 6.

35 Fig. 7 illustrates the shank of the spike as provided with a plain head 8^a. Under certain conditions, this form of head can be used.

Having now described our invention, what we claim and desire to secure by Letters 40 Patent is:

1. A spike consisting of a twisted strip of material having flat sides, and ridges or fins carried by said strip located at the meeting edges of said flat sides, each ridge or fin having a straight wall, said straight wall being a continuation of one of the adjacent flat sides, the other wall being angularly disposed relative to the other adjacent flat side. 45

2. A spike consisting of a shank, said shank being provided with a plurality of helically disposed channels, said channels having an obtuse angular formation, each channel terminating in a flat surface at one end of said shank; the combined flat surfaces forming a square, one wall of said channel being of greater length than the other. 55

3. A spike consisting of a shank twisted 60 throughout the greater part of its length, the twisted portion forming in cross-section, a parallelogram having extended corners, providing projecting fins, the said extension of the parallelogram forming one side 65 of the fin, the other side of each fin being angularly disposed to form an obtuse angle relative to the adjacent wall of the parallelogram, substantially shown and described.

Signed at New York city, N. Y., this 16th 70 day of August, 1915.

MARCEL K. SESSLER.
HEYMAN ROSENBERG.
